SUPPORT

Application filed December 19, 1928. Serial No. 327,112.

This invention relates to supports, and is particularly concerned with that type of support which is adapted to be clamped to a flange or flanges on a conventional beam or girder for suspending heavy objects such as pipes, shafts, motors and electrical fittings from the beam. It is an object of this invention to simplify and improve the construction and operation of supports of this character.

A feature of the invention is the provision of a support for clamping engagement with a beam flange in which the clamping action is increased by the application of a load, such as the weight of the member supported thereby.

A further object of the invention is the provision of a support which requires no machining but which is nevertheless adapted for effective clamping engagement with the flange of a beam regardless of slight variations in the thickness of the latter.

Other objects and features of the invention will be apparent from the following description taken in connection with the accompanying drawings, in which:

Figure 1 is an elevation showing a pair of supports attached to a conventional beam for suspending a shaft hanger therefrom;

Figure 2 is a side view of the structure shown in Fig. 1 with a portion of the support in section;

Figure 3 is a detail of a construction similar to that shown in Fig. 1, but in which the suspending bolts have been arranged immediately below the beam, rather than offset therefrom;

Figure 4 is an end view of one of the elements of the supports shown in the preceding figures;

Figure 5 is a detailed perspective view of an element of the type shown in Fig. 3;

Figure 6 shows a modified form of support;

Figure 7 is a bottom plan view of Fig. 6;

Figure 8 illustrates the application of a support to a channel section;

Figure 9 is a diagrammatic view of a clamp element and beam;

Figure 10 is an end view of a further modification of a supporting element; and

Figure 11 is a section on the line 11—11 of Figure 10.

This application is a continuation in part of our copending application Serial No. 220,030, filed September 16, 1927, and embodies a number of the improvements contained in that application together with further improvements which render the device simpler to construct, easier to install, and more positive in operation.

Referring more particularly to the drawing, one embodiment of the improved support is illustrated in Figs. 1 and 2, in which a shaft 10, journaled in a shaft hanger indicated generally at 11, is suspended from and transversely of an I-beam 12. It will be understood that the invention is not restricted to the suspension of shaft hangers and shafts, but is adapted to the supporting of various heavy members such as pipes, motors, or electrical fittings, and that the specific construction of the shaft hanger disclosed herein therefore constitutes no part of the invention and is not described with particularity. In order that the shaft may be hung transversely of the beam, a pair of supports indicated at 15 have been illustrated in Fig. 1. As is disclosed in my copending application above referred to, a single support may be used in the event that the shaft is to be suspended parallel with the beam, or a different type of hanger, requiring the use of only one support, may be provided.

Each support 15 may comprise a pair of elements 17 which serve to grip or clamp the lower flange of the beam 12 and which are retained in clamping position on the flange by the provision of means for connecting the elements. In the form of the invention shown in Figs. 1 and 2, this means comprises a plurality of clamp bolts 19 which are seated in grooves or recesses 20 formed in the lower face of each clamp element 17. It will be understood that a single bolt 19 may suffice to retain the clamp elements in position on the flange, but it is preferable to use at least two of these bolts for the purpose of obtaining added strength and safety. Fig. 2 shows a construction which permits the adjustment of the shaft hanger or other member supported

from the beam to various positions beneath or laterally of the beam, and for this purpose one of the elements 17 is formed with an extension 21. A T-shaped slot 22 extends longitudinally of the element 17 and extension 21 and is adapted to receive a bolt 24 to which the hanger or other supported element may be secured. This T-shaped slot is of such size that the head of the bolt 24 is received snugly therein in such manner as to permit adjustment of the bolt to various positions along the slot but to prevent any rotation thereof.

Since the clamp bolts 19 are disposed loosely in the grooves 20 in the lower faces of the elements 17, means preferably in the form of a plate 26 is provided to retain these bolts in operative position in the grooves. This plate is in turn retained in engagement with the lower face of the element 17 by the bolt 27 which is seated in the T-shaped slot 22 and is provided with a nut 28 or other suitable means for engaging the plate 26.

Each of the elements 17 is provided with an upstanding lug 30 extending over the lower flange of the beam 12 and adapted to contact with the upper edge only of the beam. For this purpose each lug is preferably formed on its inner side with a substantially flat surface 32 which is inclined toward the body of the beam. The degree of inclination of this surface is such that the application of a load to either of the elements 17 tending to rock the element about the point of contact 33 of the body portion thereof with the lower face of the beam, serves to wedge the element outwardly of the beam, thereby tensioning the clamp bolts 19 and increasing the grip of the element on the beam flange. The novel arrangement is clearly shown in Fig. 9 of the drawing which constitutes a diagrammatic view illustrating the manner in which the clamp cooperates with the beam. The force exerted by the tensioned clamp bolt 19 tends to move the clamp element to the left in this figure, forcing the lug 30 inwardly and upwardly, whereas the effect of the load on the bolt 24, due to the weight of the supported member, tends to move the lug to the right, and downwardly, by reason of the inclination of the surface 32, thereby opposing the action of the bolt 19 and further increasing its tension with the resultant increase in gripping action of the element and cooperating parts on the beam.

It will thus be seen that by reason of the peculiar construction of the contacting portion of the lugs 30, the supporting of heavier shafts or other members from the beam will result in causing the support to clamp the beam more securely, thus providing a maximum of safety. This construction further permits the use of the support with beams having various thicknesses of flange, the thicker flanges contacting with the inclined

surface at a point more remote from the body portion of the element. Further, the construction permits the casting of the element in one piece without the necessity of subsequent machining of any part thereof, since the element is not required to accurately fit the beam flange.

Fig. 3 illustrates a modification of the construction disclosed in Fig. 1 which is adapted to permit the suspension of the supported member directly below the beam. For this purpose the opposing clamp elements 17 are formed identically, each being provided with the T-shaped slot for the reception of the member supporting bolt. It will be seen that a slight adjustment of the supported member longitudinally of the elements is permitted, but the arrangement is not designed to allow extensive adjustment of the member laterally of the beam. One or more clamp bolts 19 are used to retain the elements 17 in position on the beam, but it will be noted that the effect of applying a load to the member supporting bolts 24 will serve to force the elements into closer engagement with the beam flange, and thereby increase the tension on the clamp bolts 19 with resulting increase in the rigidity of the support as hereinbefore described.

Fig. 6 shows a modification of the foregoing constructions in which one of the elements 17 has been replaced by a hooked bolt 34 which also serves the function of retaining the element 17 in position on the flange and thus constitutes an effective substitute not only for one of the elements 17, but for the bolt 19 as well. As in the preceding constructions, it is preferable to use at least two of these hooked bolts 34 for the purpose of obtaining additional security and strength.

It frequently happens that the foot or other portion of the supported member which engages the base of the element 17 is not of sufficient size to cover the grooves 20 in the element, to prevent displacement of the clamp bolts 19 from the grooves. Under such conditions, it is of course necessary to provide a plate 26, such as has been described in connection with Figs. 1 and 2, to close the grooves, and this plate may be conveniently placed beneath the foot or other engaging portion of the supported member, as shown in Fig. 6, the member supporting bolt 27 serving to retain the member and plate in position on the lower face of the element.

When the element 17 is secured on the beam in the manner disclosed in Figure 6 it is possible for the supporting bolt to loosen and to slip out of the support through the open end of the T-shaped slot. In order to prevent the supporting bolt from working out of the slot, the element 17 may be constructed as shown in Figures 4 and 5, in which one side of the open end of the T slot

is closed as indicated at 23. This construction is ordinarily not required in any arrangement involving the use of two facing supporting elements 17, as for instance in Figure 3, in which there is no possibility of displacement of the supporting bolts owing to the construction of the supported member which maintains the bolts in spaced relation.

Fig. 8 illustrates a different form of the invention in which the support is applied to a channel section. For the purpose of applying the support to a section of this type, a hole 36 is drilled or otherwise formed in the channel section, and the bolt 35 which is formed with a hooked end 37 engaging in the recess 36, is disposed in the groove 20 of the element 17. It will be noted that this bolt serves to retain the element in position on the flange of the beam, and that the application of a load to the member supporting bolt 24 will serve the same function as in the other forms of the invention, namely the increasing of the clamping action on the beam flange.

While the grooves 20 for receiving the clamp bolts are simple to construct and the supported element or the plate 26 serves to effectively hold the clamp bolts in position within the grooves, it is sometimes found convenient to construct the clamp element in the manner disclosed in Figures 10 and 11, in which the slot 20 is closed at one end as indicated at 40, and a hole 41 is provided 35 to receive the clamp bolt 19. It will be seen that this construction likewise effectively prevents displacement of the clamp bolts, and is capable of use in any of the various modifications disclosed in the remaining figures. The action of the clamp bolt and the supporting element in gripping the beam flange is of course not altered by construction of the element in this manner. It will furthermore be apparent that the construction 40 of the element illustrated in Figures 10 and 11 may be used either with or without the retaining plate 26. For instance, in the arrangement shown in Figure 3, one of the elements 30 might be constructed in the manner shown in Figures 10 and 11, while a co-operating element 30 of the type shown in Figure 4 might be used on the other side of the beam in conjunction with a plate 26 for preventing displacement of the clamp bolts 45 from grooves 20 in the last mentioned element.

It will be seen that the support described herein is extremely simple to construct and relatively inexpensive by reason of the elimination of machining, and the fact that the elements are adapted to various sizes of beams having different flange thickness.

It is also apparent that the invention disclosed herein is applicable to practically any 55 installation, and may be adapted to the vari-

ous types of beams by slight modification and interchanging of the various parts. The several modifications illustrated serve to disclose various specific embodiments of the invention, but it is to be understood that these specific embodiments are only illustrative and that the invention includes all such adaptations as fall within the scope of the appended claims.

Having thus described the invention, what is claimed as new and desired to be secured by Letters Patent is:

1. In a support for suspending members from beams, the combination with a clamp element comprising a body portion adapted

70 to lie beneath the lower flange of a beam, and having one end in engagement therewith, and an upwardly extending lug portion formed at the other end of said body portion and having a surface adapted for direct engagement with the upper edge only of the flange, the upper portion of said lug extending inwardly toward the beam and the said surface thereon being so inclined that downward swinging movement of said element

75 about its point of engagement with the lower surface of the flange serves to wedge the element in a direction away from the central portion of the beam, and means exerting tension between said element and another portion of the beam for retaining the element in position on the beam, and means for supporting a load on said element outwardly of the point of engagement of said element with the upper edge of the flange whereby 80 such load tends to slide the said inclined surface relatively to the flange for increasing the tension exerted by said first named means and thereby forcing said element more tightly into engagement with said flange.

2. In a support for attachment to a beam, the combination with a recessed element for engaging the beam flange, of means for exerting tension on said element to retain the latter in position on the flange, a portion of 85 said means being disposed in said recess, said element being provided with a slot adapted to receive a hanger bolt therein, a bolt in said slot, and a plate retained in position by said bolt and serving to close the said recess to 90 retain said means therein.

3. In a support for attaching members to beams, the combination with a recessed element for engaging a beam flange, of means for exerting tension on said element to retain

100 the latter in engagement with said flange, a portion of said means being disposed in said recess, said element being provided with a slot adapted to receive a bolt therein, a plate adapted to close the said recess to retain 105 said means therein, and a bolt disposed in said slot and serving to secure a member to the element and to retain said plate in retaining position.

4. In a clamp for securing members to

beams a clamp element comprising a substantially flat body portion adapted to lie beneath the lower flange of said beam, an integral upwardly extending lug portion adapted to directly engage a portion of the upper part of said flange, the under side of said body being provided with a transverse groove adapted to receive a clamp bolt, and a T-shaped slot for receiving a member supporting bolt to permit sliding adjustment thereof along the slot, said bolt having a non-circular head to prevent rotation thereof within said slot, and a plate for closing said groove to retain said clamp bolt therein, said plate being adapted to be held in operative position by said member supporting bolt.

5. In a device adapted to be clamped on a flanged beam, the combination with an element for engaging the beam flange and provided with a groove extending along a portion only of that face of the element remote from the beam flange and an aperture constituting an extension of said groove and isolated from the said face, of means for exerting tension on said element to retain the latter in position on the flange, a portion of said means being disposed in said groove and said aperture.

6. In a support for suspending members from beams, the combination of a clamp element comprising a body portion having an upper face adapted to engage and lie beneath the lower flange of a beam, and an upwardly extending lug portion having a surface adapted to engage the upper edge of the flange, and provided with a lower face grooved throughout a portion only of its length, and having an aperture constituting an extension of said groove, and means exerting tension between said element and another portion of the beam for retaining the element in position on the beam, a portion of said means lying in said groove and extending through said aperture.

7. In a clamp for securing members to beams, a clamp element comprising a substantially flat body portion adapted to lie beneath the lower flange of said beam, an integral upwardly extending lug portion adapted to directly engage a portion of the upper part of said flange, the under side of said body portion being provided with a transverse groove adapted to receive a clamp bolt, and a T-shaped slot for receiving a member supporting bolt to permit sliding adjustment thereof along the slot, said bolt having a non-circular head to prevent rotation thereof within said slot, said slot being closed at both ends to prevent the bolt from moving out of the slot.

In testimony whereof we hereunto affix our signatures.
